UNITED STATES PATENT OFFICE.

GEORGE A. ROBINSON, OF QUINCY, MASSACHUSETTS, ASSIGNOR TO PNEUMATIC SCALE CORPORATION, LIMITED, OF QUINCY, MASSACHUSETTS, A CORPORATION OF MAINE.

END FOLDING AND SEALING MACHINE FOR CARTONS.

1,338 749.

Specification of Letters Patent.

Patented May 4, 1920.

Application filed June 23, 1919. Serial No. 306,084.

To all whom it may concern:

Be it known that I, GEORGE A. ROBINSON, a citizen of the United States, residing at Quincy, county of Norfolk, State of Massachusetts, have invented a certain new and useful Improvement in End Folding and Sealing Machines for Cartons, of which the following is a specification, reference being had therein to the accompanying drawings.

The invention is for an improvement in machines for folding and sealing the end forming flaps of cartons.

Most of the knockdown cartons are formed of a single sheet of material which is creased or scored to form four side-forming panels with a side sealing lap, and each panel has at each end a flap. The flaps at one end of the panels are intended to be folded and sealed to form the bottom of the carton, and the flaps at the other end are intended to be folded and sealed after the carton is filled to close the top of the filled carton. The present invention relates to mechanism especially intended for folding and sealing the bottom forming flaps as will be described with more particular reference to the bottom. Preliminary to the folding and sealing of the bottom forming flaps, the side sealing lap has been sealed and the carton is squared-out into tubular form with the end flaps distended, and the squared-out tubular carton is then slipped onto a forming block shaped to the interior contour of the squared-out carton and then the bottom forming flaps are folded against one end of the said block and the overlapping flaps are sealed together. The machine may however be employed in folding and sealing the top of the carton and the claims are intended to cover a machine of the character hereinafter described whether used as a bottom sealer or as a top sealer.

In machines of this character it is necessary that the folding devices and the gluing devices shall not only come in proper sequence with relation to each other, but also they should be properly timed with relation to each other's movements so that there will not be any interference between the folding devices and the gluing devices. It is also desirable that when one of the flaps is folded it shall be held in folded position until the next overlapping flap comes up to hold it, and that the last folded flap shall be held

in position for a period of time until the sealing has become sufficiently dry to prevent its becoming unsealed. As heretofore constructed, even though the parts are properly adjusted and timed when the machine is new, yet when the parts become somewhat worn by use there is apt to be more or less interference. One object of the present invention is to have the gluing devices and the folding devices and the retaining devices definitely fixed with relation to each other, and constructed in such a manner that any lost motion or wear in the parts will not materially change their relation to each other.

The cartons are usually rectangular in form, being wider in one direction than in the other, so that they have two opposite wide panels and two opposite narrow panels. The end forming flaps connected with the two narrow panels, which we will term the end panels, are usually shorter than the longer dimension of the bottom of the carton, so that these two flaps connected with the end panels either slightly overlap each other without extending clear across the bottom or sometimes barely meet, and still again there is a space between them. Each of the other two flaps, however, that is those connected with the broad or side panels, is usually of sufficient length to cover the entire bottom of the carton, one overlapping the other.

One feature of the invention consists in mounting the folding mechanism for the two narrow flaps, and also the gluing mechanism, upon a rotary spider which moves in a manner to successively bring the folding mechanisms for said two flaps and also the gluing mechanisms into operative position while the carton is held upon its forming block. Another feature of the invention relates to the means for folding the two opposite side flaps successively after the end flaps are folded and glued. Another feature of the invention consists in mounting the spider upon a rotary shaft and driving the folding mechanism for the two side flaps by means of devices mounted on the same shaft as that on which the spider is mounted.

Another feature of the invention consists in mounting the gluing rolls and the flap retainers on the rotary spider which rotates in a plane at right angles to the plane of the

end of the block against which the bottom forming flaps are folded. So far as I am aware, it is entirely new with me to mount the glue rolls, the flap folders and the flap 5 retainers, either one or two or all three of the above, on a rotary spider which rotates in a plane at right angles to the end of the block on which the flaps are folded.

Another feature of the invention consists 10 in mounting the gluing roll on a spring-seated slide so that the gluing roll can yield to the pressure as it wipes over the surface of the flap, whether the gluing roll is mounted on a rotary spider or otherwise mounted, 15 and whether it travels in a circular path or in a straight path.

Another feature of the invention consists 20 in having one glue roll to glue the under surface of the two end flaps, that is the two short flaps which are first folded and a second glue roll independent of the first glue roll to glue the first folded side flap after it is folded over the folded end flaps.

Another feature of the invention consists 25 in the method by which the glue roll is restricted from coming in contact with the end of the block and thereby smearing the block in case there happens to be no carton on the particular block when the glue roll in 30 course of rotation of the spider would naturally engage the carton, if there was a carton on the block.

Another feature of the invention consists 35 in means for preventing the glue roll from coming into contact with the block in the space between the two narrow or short end flaps which are first folded where the end flaps are so short that they do not meet. I believe that this idea is broadly new with me.

40 Another feature consists in the form of flap retainer which retains the flap in folded position, and consists in forming the contacting surface on the arc of a circle with the some center as the spider.

45 Another feature consists in mechanism which cause the glue roll carried by the spider to strike the flap at a tangent, so that whenever the size of the block and the carton are changed to either wider or narrower the 50 glue roll will not strike the side or corner of the block or strike the bottom of the block on the rising curve.

The mechanism of the present invention is intended to be used in connection with a 55 machine having a horizontally rotary spider with depending forming blocks to hold a squared-out carton during the folding and sealing of the bottom forming flaps, such for instance as shown in Patent No. 736,237 60 to W. H. Doble, dated August 11, 1903, in which the rotary spider has four depending blocks at ninety degrees apart and provided with mechanism for rotating it intermittently so as to bring at each period of movement one of the depending forming blocks

70 with the carton held thereon into position to be acted upon by the folding and sealing mechanism. Such rotary spider does not of itself form a part of the present invention and any other suitable holding device for the 75 carton may be employed, the present invention not being limited to use in connection with any particular carton holding mechanism. For this reason the spider which holds the forming blocks is not shown, only two of the holding blocks being shown in proper relative position for convenience of illustration of the present invention.

75 The invention will be fully understood from the following description when taken 80 in connection with the accompanying drawings, and the novel features thereof will be pointed out and clearly defined in the claims at the close of this specification.

85 In the drawings, Figure 1 is a front elevation of mechanism embodying the invention and shows the lower portions of two forming blocks which carry the cartons to be folded and sealed. These forming blocks are supposed to be depending from a rotary 90 spider such as previously referred to, and to be ninety degrees apart from each other in the circular path of movement of the spider.

95 Fig. 2 is a side elevation of the mechanism shown in Fig. 1 as viewed from the right of Fig. 1.

100 Fig. 3 is an enlarged detailed view of the spider which carries the folding and gluing devices and some of the other parts of the machine, viewed as in Fig. 1, the bearing bracket and all parts in front of the spider being removed for the sake of clearness.

105 Fig. 4 is a detailed view enlarged of the mechanism for operating the first folding finger.

Fig. 5 is a plan view of the glue feed roll, operating mechanism and glue tank.

110 Fig. 6 is a detailed view showing the mechanism for controlling the first glue roll to prevent gluing the block when there is a gap between the adjacent ends of the first two folded flaps.

Fig. 7 is a detailed view of the side flap folding rolls in plan view.

115 Fig. 8 is a plan view of the mechanism for operating the carton clamping mechanism and the flap retaining finger.

Fig. 9 is a plan view of the mechanism for locking the cam which controls the glue 120 rolls.

125 Referring now to the drawings, *a* represents one of the forming blocks on which a carton *c* is held and upon which the folding operation is in process of being performed. A forming block *b* is shown as in position to be next brought into position for the folding and sealing operation, and is supposed to be ninety degrees away from the block *a*; said blocks depending from the 130

horizontal arms of a spider not shown, so that the forming blocks in their path of travel will move in a circular path describing a vertical cylinder.

5 A horizontal shaft 1 is journaled in bearings in a bracket 2. Fixedly mounted on said shaft 1 as for instance by a key 3 is a spider 4, which when the shaft rotates revolves in a vertical plane. Said spider is 10 formed with two radiating portions 5 and 6 which radiate from the said shaft as a center at an angle to each other.

15 The radiating portion 5 has extending therefrom an arm 7 which carries at its end 15 a flap folding member 8, and an arm 9 which carries at its end a flap retaining member 10, which will be more particularly described hereinafter.

20 There is mounted on the shaft 1, by means which will be hereinafter described more fully, a folding arm 11 adapted to fold the first end flap, 12, the folding member 8 being adapted to fold the second end flap, 13, after the flap 12 has been folded.

25 The two side flaps, 14 and 15 respectively, will be afterward folded in successive order by the folding rolls 16 and 17 shown in Fig. 2, by a lateral movement as will be more particularly described hereinafter. 30 These latter folding rolls 16 and 17 are not mounted on the spider 4 but are moved independently of the spider, although actuated by mechanism so controlled as to properly time the movements of the side 35 folding rolls with relation to the movements of the folder finger 11 and the folder member 8 carried by the spider.

The mechanism for actuating the folding arm 11 for folding the first flap is as follows:—

40 The lower end of said arm 11 is connected with a boss 18 projecting from a segment gear 19 mounted loosely on the spider shaft 1, see Fig. 4. Preferably the said arm 11 is screw threaded at its lower end to engage with a threaded hole in the boss 18 so that the arm may be adjusted.

45 The segment gear 19 meshes with a sector gear 20 which is rotatably mounted on a stud 21, said stud 21 being mounted fast in the spider 4. The sector gear 20 has an arm 22 which carries at its outer end a roll 23. A cam 24 is mounted fast on the bracket 2, or mounted in some other way so as to be 55 stationary, and the spider shaft 1 passes loosely through said cam. The roll 23 carried by the arm 22 of the sector 20 engages with the periphery of said cam 24. As said sector is carried by the spider in the 60 direction indicated by the arrow, that is counter clockwise, the said sector gear will also have a movement on its own axis and be caused to partially rotate as it rides over the periphery of the cam, rocking in one 65 direction or the other according to the varia-

tions in the cam, but at the same time it is moved bodily with its stud 21 in the direction in which the spider rotates. By reason of the engagement of the sector 20 with the segment gear 19, said segment gear 19 will 70 also be given a rocking movement on the spider shaft 1 and the boss 18 will rock in a vertical plane. This rocking movement of the segment gear 19 and boss 18 gives an oscillating movement to the arm 11. The 75 periphery of the cam 24 is of such contour that although the spider 4 rotates continuously counter clockwise, as shown by the arrow in Figs. 1 and 3, yet at a certain point in the rotation of the spider, that is 80 when the roll 23 rides over the high part of the cam, that is from the point marked Z to the point marked Y, the sector gear 20 will be rocked in such a direction that the segment gear 19 will cause the arm 11 85 to swing in a direction opposite to the general direction of travel of the spider, that is from the left to the right as viewed in Figs. 1, 3 and 4 and thereby fold the end flap 12 up against the bottom of the form- 90 ing block, as shown in Figs. 1 and 3. In those figures the said folding arm has nearly completed its folding operation and as will be seen in Fig. 4 the roll 23 is just about to ride onto the high part of the cam. In 95 the continued movement of the spider while the roll 23 is riding from the point Y on the cam to the point Y' there is a dwell, and while riding from the point Y' to X on the cam the sector gear and the segment gear will 100 be rocked in the reverse direction thereby causing the arm 11 to swing back out of engagement with the flap 12 to give opportunity for the folding member 8 to fold the second end flap 13 without interference. 105 The folding finger 11 will be retained in this outward position while the spider completes its rotation, that is until the roll 23 has traveled from the point X to the point Z of the cam, this portion of the cam surface 110 being concentric with the spider shaft, so that the arm 11 will remain stationary with relation to the spider although it revolves bodily with the spider around the axis of the spider.

115 The folding member 8 is carried by the arm 7 and rigidly connected with the spider. The forward end of the folding member 8 will engage the second flap 13 and partially fold it before the first folding member 11 begins to retreat, as shown in Figs. 1 and 3. The arms 11, however, begin to retreat immediately following the position shown in Figs. 1 and 3, and retreat fast enough to keep out of the way of the flap 13 as the 120 folding of said flap 13 is completed by the member 8.

125 The folder member 8 is preferably some- what U-shaped in plan view, the bow of the U shape being at the left hand end 8^a as 130

viewed in Fig. 3 which engages with the flap 13. The legs of the U preferably flare away from each other toward the other end, said other end being open between the two legs of the U to receive the glue roll 25 and particularly for the purpose of spreading the two side flaps 14, 15 so that they will not interfere with the glue roll. As this particular feature of construction of the 10 folding member 8, namely the flaring U shape, is not claimed as a part of the present invention, it is not shown in the drawings in detail but is described as above for the purpose of more clearly understanding 15 the general construction.

The glue roll 25 is mounted on a radially 5 slidable spring seat as will now be described. The glue roll 25 is journaled in the arms of a U-shaped bracket 26 which is secured to a 20 slide member 27. Said slide member 27 is slidable in grooved guides 28-28 formed in the inner sides respectively of the folder arm 7 and the flap retainer arm 9 connected with the radiating arm 5 of the spider. 25 The folder arm 7 and the flap retainer carrying arm 9 are separated from each other by a slot within which the slide member 27 moves in said guides 28-28. The said slide member 27 is carried by arms 29 and 30 respectively, the arm 29 being pivotally connected at one end by a pin 301 to the flap retainer arm 9 and at its other end it is pivotally connected by a pin 31 to the slide 27. The arm 30 is pivotally connected at 30 one end by a pin 32 to the flap retainer arm 9 and at its other end it is pivotally connected to the slide by a pin 33. The pin 33 projects to some distance laterally outside of the slide and carries at its end a roll 34 adapted to be engaged by a cam surface 37 for the purpose which will be described 35 hereinafter.

A spring 36 is coiled around the pin 32, and has one arm which rests upon the hub 45 35 of the spider shaft 1, and another arm shown in dotted lines in Figs. 1 and 3, which bears against the under side of the hub of arm 30, the stress of said spring 36 being such that it tends to press the slide 50 27 radially outward. This outward pressure is sufficient to hold the slide and therefore the roll 25 far enough outwardly to cause the glue roll to engage the under surface of the flap 13 during the rotation of the 55 spider. As the path of movement of the spider would normally carry the glue roll bodily in an arc of a circle, and as the glue roll should travel in a straight line when it 60 wipes over the surface of the flap 13, the spring seat of the slide 27, in which the glue roll is mounted, allows the slide to be pushed radially inward to compensate for the tendency otherwise to move in a convex path. The means for causing the glue roll to travel 65 in a straight line when it moves over the

surface of the flap consists of the cam 37 which is engaged by the roll 34 as will be more fully described hereinafter.

As one end of each of the arms 29 and 30 is fixed to the arm 9, the swinging end of said arms 29 and 30 while the slide is moving in and out must move in the arc of a circle; therefore the slide 27 must be allowed sufficient lateral clearance in the guides 28-28 to allow for this movement. 70 For that reason the grooved guideways must be sufficiently deep to allow for such lateral movement. This extra clearance is shown by the space between the dotted lines as shown in Fig. 3. The two inner dotted lines 75 indicate the edges of the slide, and the two outer dotted lines indicate the depth of the grooved ways. The glue roll 25 will travel over the flap 13 and thence over the flap 12.

After the flaps 13 and 12 have been traversed by the glue roll 25, the first side flap 14 will be folded over onto the flaps 13 and 12, but it is important to provide some means for holding the flap 13 from falling back after it has been traversed by the glue 80 roll 25 until the side folding roll 16 can come into engagement with the side flap 14 to bring it up against the flaps 13 and 12. This is accomplished by a flap retaining member 10, which is carried by the arm 85 9 on the spider and swings lightly up into engagement with the flap 13 directly behind the glue roll 25 and before the flap 13 can fall down any great distance. It is not necessary that the flap retainer 10 shall hold the 90 flap 13 pressed up against the flap 12, but it should hold it up sufficiently far so that it will be in position to be engaged and pressed upward against the under side of the block by the folding of the flap 14. 105

This flap retainer 10 is preferably a thin strip of sheet metal secured to the outer end of the arm 9 and which is seen in side elevation in Figs. 1 and 3 and in edge view in Fig. 2. The outer edge of this flap retainer 10 is preferably on the arc of a circle concentric with the spider shaft 1. The parts of the mechanism are timed so that the tip end of the retainer 10 will ride off of the flap 13 in ample time to prevent interference with the side flap folding roll 16. The flap retainer 10 is made thin in order not to scrape the glue from the under side of the flap 13, and for the same reason it 110 preferably does not extend out far enough radially to press the flap 13 against the under side of the forming block, so that the only pressure of the flap 13 upon the retainer is due simply to the weight of the flap. 115

As already stated it is desirable that the glue roll shall travel in a straight line at the time it engages with the flap 13, that is that it shall change from a circular path to a straight path tangential to the circular 120 125 130

path of the periphery of the glue roll. Means for accomplishing this are as follows: A cam plate 371 is pivoted at one end by a pin 372 to one side of the bracket. Said 5 plate has on one side a cam flange 37 which rests on the roll 34. Said flange is formed with a downward drop on a curve, and it is so located that just before the glue roll 25 is ready to engage the flap 13, the roll 34 10 carried on the stud 33 of the arm 30 will engage the under side of the curved part of said flange 37 which serves as a cam, and first lift the cam plate until the cam flange strikes the stop screw 375 unless the cam 15 plate is locked against rising as provided for when there is no carton on the block, as will be hereinafter described, then the continued movement of the spider will cause the roll 34 to ride on the cam while the 20 cam is stationary and this will draw the slide 27 downward just enough to compensate for the upward swing of the spider arm. This will continue until the glue roll passes the highest point in its arc of movement, then the roll 34 will engage the upward curve of the cam 37 to compensate for the normal downward swing of the glue roll, thus causing the glue roll itself to travel in a straight line during all of the 25 time that the roll 34 is riding on the cam surface of the flange 37. The stop pin 375 is adjustable and should be so adjusted as to allow the cam to be lifted enough so that the slide may move out far enough for 30 the glue roll to wipe against the under face of the flap 13. The stop pin is shown as a screw which is screwed down through a flange 373 projecting from one side of the bracket 374. See Fig. 1.

40 The means to prevent the glue roll 25 from engaging the bottom of the carton holder block if there is a gap between the adjacent ends of the flaps 12 and 13, and yet allow it to glue both of said flaps, is 45 as follows: Secured to the cam plate 371 is an arm 381 carrying a roll 382 projecting therefrom. A cam block 38 is secured to the flap retainer arm 9 in a position where its inclined edge 383 will engage the roll 382 just before the glue roll 25 passes off 50 of the flap 13. The block 38 is set so that the inclined edge 383 will act as a cam and by its engagement with the roll 382 will depress the cam plate 371, thereby also 55 retracting the slide 27 by reason of the cam flange 37 pressing on the roll 34 carried by the arm 30. This will cause the glue roll to drop down far enough to not contact with the block 38. As soon as the spider has 60 rotated far enough for the cam block 38 to ride off of the roll 382, the cam plate 371 is free to respond to the outward push of the roll 34 against the cam flange 37 under the stress of the spring 36. The cam block 65 38 is of such size that it will release the

cam plate 371 as soon as the glue roll 25 has passed the gap between the flaps 13 and 12.

The block 38 is preferably secured to the spider in such manner that it may be readily detached and a block of different size substituted, according to the length of gap between the flaps. If screws 39 are employed to attach the block, the different sized blocks may have screw holes spaced so as to fit the screw holes in the spider. 75 If the cartons have flaps which do not leave a gap between them, the block 38 will be detached and entirely left off.

The mechanism for folding the side flaps will now be described, first considering the 80 mechanism for folding the first side flap 14. A folder roll 16 is mounted in a forked arm 40, which is pivoted on a pin 41 between the vertical forked arms 42 of a bracket 44 which is secured to the slide 45, said slide 85 being slidably mounted in grooved ways in a bracket top 46. The bracket 44 is preferably adjustably secured to the slide 45, so that it may be adjusted to a more forward or backward position. The means shown is 90 a screw 441 which passes through an elongated slot in the bracket and is screwed into the slide. A spring 47, coiled around the pin 41, has one arm which engages a shoulder 42 as a stop, and another arm which 95 engages a shoulder on the roller-carrying arm 40, said arms tending to spread so that the stress of the spring tends to lift or turn upward the arm 40 and the roll 16.

The slide 45 is actuated at the proper time, 100 after the two end flaps have been folded and glued, to move inward, that is to the left as viewed in Fig. 2, to engage the downwardly extending flap 14 and fold it up against the two previously folded flaps. The mechanism for doing this is as follows:—On the under side of the slide 45 is secured a rack 48 which projects down in the slot on the under side of the bracket top 46. A sector gear 49 carried on the arm 50 of a bell crank 110 lever engages with said rack 48. Said bell crank lever is pivoted on a stud 51. A spring 52 is connected at one end with the arm 50 between the fulcrum point on the stud 51 and the toothed sector end 49, the 115 other end of said spring being secured to the stationary bracket 2. Said spring is always under tension and tends to pull the sector 49 toward the left from the position shown in Fig. 2, but is normally restrained therefrom by means which will presently be described. When it is free to pull the said sector gear to the left, it will cause the slide 46 to move to the left carrying with it the arm 40 and the folding roller 16, causing it 120 to engage the flap 14 and fold it up against the previously folded flaps 12 and 13.

The means for normally restraining, however, the said movement of the sector arm 50 is as follows: The bell crank of which the 130

arm 50 is a part has an arm 53 carrying a roller 54 which rides on the periphery of a cam 55 mounted on an extension of the spider shaft 1. The peripheral surface of 5 the cam 55 is of such shape that the arm 50 and therefore the sector gear 49 will be held in the retracted position shown in Fig. 2 until the proper time, after the two end flaps 12 and 13 have been folded. At that 10 time a drop in the periphery of the cam will come around to the roll 54, thus allowing the arms 53 and 50 to respond to the pull of the spring 52. This will cause the sector gear 49 to actuate the slide 45 toward the 15 left as viewed in Fig. 2, causing the folding roll 16 to move forward and fold up the flap 14 against the flaps 12—13. A slight further rotation of the cam 55 will bring the roll 54 up out of the depression in the 20 cam causing the sector arm 50 to rock backward and therefore carrying back the slide and the folder roll 16.

After the flap 14 has been folded it is necessary that its under surface should be 25 glued, and then the fourth flap 15 will be folded up against flap 14. It is important, however, that the flap 14 should be held against dropping down after the folder roll 16 retreats and during the gluing of the flap 30 14. The flap retaining and gluing mechanism for the flap 14 is as follows:—The arm 6 is bifurcated similar to the arm 5, forming a slot between a flap retaining arm 56 and a second flap retaining arm 57, whose purpose 35 will be hereinafter described. A flap retainer blade 58 is mounted on the end of the arm 56, said retainer blade 58 being curved on its outer edge on the arc of a circle concentric with the spider shaft and 40 being made thin for the same reason as already described with relation to flap retainer 10. Its radius is preferably slightly less than the distance from the center of rotation of the spider to the flap 14 so that 45 when the retainer arm reaches its highest point in its path of rotation it will not press the flap against the under side of the block but will serve merely to lightly support the flap 14 if the flap 14 drops down a very 50 slight distance in the same way as described for the flap retainer 10 to engage the flap 13. The flap retainer 58 will come up into position to support the flap 14 just as the folder roll 16 withdraws.

55 A glue roll 59 is journaled on a stud mounted in a forked bracket 60 carried on the end of a slide 61 which moves in grooved ways 62 in a similar way as the glue roll 25 is mounted, and is also actuated in a similar way to the glue roll 25, that is by the arms 63 and 64. The arm 63 is pivoted at one end to the arm 57 and at its other end to the slide 61, and the arm 64 is pivoted at one end to the arm 57 and at its other end 60 to a stud 65 projecting from the slide 61 and

carrying at its outer end a roll 66. A spring 67 is provided similar to the spring 36 and similarly connected and engaging the stud 65 and the hub 35, said spring having a tendency to thrust the slide outward, 70 and yielding as the roll engages the cam 37 to cause the glue roll to travel in a straight path.

Immediately after the flap 14 has been glued, the flap retaining blade 68 carried by 75 the arm 57 comes into position to help support the flap 14 and prevent it from dropping until the flap 15 is turned up far enough to hold the flap 14. The means for folding the flap 15 are very similar to the folding mechanism 80 for the flap 14. The flap folder roll 17 is carried between the branches of the forked arm 69 pivoted on the stud 70, said stud 70 being journaled in forked bearings 71 rising from a bracket 72 which is mounted 85 on a slide 73 in a bracket top 74. The bracket 72 is adjustably secured to the slide in the same manner as the bracket 44 is secured to the slide 45. See Fig. 7. The slide carries on its under side a rack 75 90 which is engaged by a sector gear 76 carried by an arm 77 of a bell crank lever mounted on a shaft 78, said lever having an arm 79 carrying a roller 80, which engages with the periphery of a cam 81 mounted on an 95 extension of the spider shaft 1. A spring 83 is provided to actuate the folding movement of the slide 73 and the folder roll 17. There is also provided a spring 84 connected with the folder arm 69 for the same purpose 100 as the spring 47 connected with the folder arm 40. The cam 81 is formed with the cam surface so shaped as to permit the lever arm 77 to respond to the pull of the spring 83 at the proper time to fold the 105 flap 15.

After the last flap has been folded a presser device 178 will come into engagement with the said last folded flap to press it and the previously folded flaps against the block with sufficient force and for sufficient length of time to cause the flaps to all adhere together. The presser mechanism is not shown in detail as it forms no part of the present invention.

110 After the last flap 15 has been folded, it is important that the said last flap should be held from dropping down before the presser member, previously referred to, has opportunity to engage the flap and press it up firmly against the block. This intermediate retaining device is as follows: An arm 170 is mounted on a vertical pin 171 in such a manner as to be capable of an oscillating movement in a horizontal plane, 115 and carries a finger at 172 having a bent portion 173, which when the said arm 170 oscillates in one direction is adapted to be swung forward directly underneath the last folded flap of the carton. Rigidly connect- 120

ed with the arm 170 so as to move therewith is an arm 174 which carries a roll 175 which engages with the periphery of a cam 176. A spring 177 retains the said roll 175 in constant engagement with said cam. When the roll 175 is on the high part of the cam, the finger 173 will be in a retracted position, as shown in Fig. 8. When, however, the roll 175 rides from the high part 10 of the cam into the drop in the cam, the finger 173 will be thrown forward just beneath the forming block in a position to engage the folded flap. This is timed to occur just as the last flap is folded.

It is important that the cartons should be clamped firmly to the forming block during the folding and sealing of the bottom flaps, so that it shall not slip off of the block or slip down out of position. Mechanism 15 is shown in the drawings for that purpose, there being provided a clamp for each of two opposite sides. The clamping mechanism for one side of the block is as follows: An adjustable stud 85 carried by an arm 86 of a bell crank lever is provided with a clamp 87 which is adapted to engage one side of the tubular carton to clamp it against the block. Said bell crank is fulcrumed on a shaft 88 mounted in a fixed 20 part of the frame. Said bell crank has a horizontal arm 89 carrying a roller 90 which engages with a cam 91 on a vertical rotary shaft 92. A spring 93 has one end connected at 94 with a fixed part of the frame, 25 and at its other end is connected with a projection 95 rigidly connected with the arm 89 of the bell crank. The stress of this spring tends to hold the clamp 87 firmly against the side of the carton. The cam 91 30 is formed with a rising portion 96, and when during the rotation of the shaft 92 the roller 90 rides up on the high part 96 of the cam, it will rock the bell crank on its fulcrum 88 and turn it backward so as to 35 withdraw the clamp 87 from engagement with the carton. The parts are all so timed with relation to each other that the roll will ride up on this high part of the cam at the proper time to release the clamp from the 40 carton, and will again ride off of the high part of the cam to permit the clamp to respond to the stress of the spring at the proper time, when the spider which carries the forming blocks brings a forming block 45 with a new carton on it into position to be folded.

The clamping member for the opposite side of the carton is similar in most respects to the clamping mechanism already described, but slightly different in detail, and its release is controlled by the mechanism for releasing the first clamping member. The second clamping mechanism is as follows: A clamp 97 is carried by a stud 98 60 adjustably connected with an arm 99 fast on

shaft 100. A spring 101 tends to hold the arm in position to maintain the clamp in clamping engagement with the carton; said spring 101 is a push spring while the spring 93 is a pull spring. An arm 102 which is 70 rigidly connected with arm 99 has adjustably connected therewith a stop screw 103, said stop screw 103 being adjustable and engaging with the top 104 of the bracket, which limits the rocking of the arm. 75

Fast to the shaft 100 is a horizontal extending arm 105 with which is loosely connected the upper end of the downwardly depending connecting rod 106, the lower end of said connecting rod being bent at an 80 angle and connected with an arm 107 which in turn is connected with one end of a horizontal rocker shaft 108. The other end of the rocker shaft 108 has connected therewith an arm 109 which in turn is connected 85 with the bent lower end of the vertical connecting rod 110, the upper end of said rod 110 being connected with one end of an arm 111 whose other end is fixedly connected with the shaft 88 on which the bell crank 90 90 is mounted. By the connections thus described when the bell crank 86 is rocked by the engagement of the high part of the cam 96 with the roll 90 to retract the clamp 87, the opposite clamp 97 will also be re- 95 tracted.

The means by which the glue roll is prevented from being projected out far enough to engage the bottom of the forming block when there is no carton on the forming 100 block, will now be described: Under certain conditions, such as when there is a carton on the block the cam plate 371 with cam 37 is permitted to be lifted by the roll 34 until the cam engages the stop pin 375. 105 Normally it is retained in its lowermost position, as shown in Fig. 1. If it is locked in that lowermost position, then when during the rotation of the spider the roll 34 on the arm 30 rides on the under side of 110 the cam 37, the slide 27 which carries the glue roll 25 will not be permitted to move out far enough radially under the impulse of the spring for the glue roll to engage either the carton or the block, although the 115 glue roll will still move in a straight path as it passes under the block, by reason of the cam 37. Means are provided to thus lock the cam plate 371 in its lowermost position each time after the block-carrying 120 spider, (not shown), begins to move to carry away the block on which a carton has had its bottom flaps folded and sealed, so that when the next forming block comes around into position the glue roll will be 125 held in its backward position unless there is a carton on the block. Means are provided whereby if there is a carton on the next following block, the lock will be released by the actuation of one of the down- 130

ward depending flaps. When the cam plate is thus unlocked, it is permitted to be lifted a limited distance by the roll 34 on the arm 30 before the roll rides under 5 the curved part of the cam 37, the amount of the lift being sufficient to permit the slide 27 which carries the glue roll to be moved radially outward far enough for the glue roll to wipe against the under side of 10 the flap 13, as previously described.

The locking means for locking the cam 37 in its lowermost position are as follows: See Figs. 1, 2 and 9. A lug 115 projects laterally from one side of the plate 371. A 15 bracket 116 is fixedly secured to a vertical rocker shaft 117, as shown in the drawings, Figs. 1 and 9. Said bracket is formed with two lugs 118 and 119, apertured to receive the shaft 117 which fits tightly in said apertures so that the bracket will rock with 20 the shaft. A finger 120 projects laterally from the upper end of the bracket, and is adapted to extend over the top of the lug 115 and when in that position it will prevent 25 the cam plate 371 from rising, thus locking it so that the slide 27 which carries the glue roll will be prevented from being moved out far enough for the glue roll to come in contact with the block during the 30 rotation of the spider, provided the lock is not released.

Said rocker shaft 117 extends vertically downward, (see Figs. 1 and 2) and at its lower end is connected with one end of an 35 arm 121, the other end of the arm being connected with one end of a rod 122, the other end of said rod 122 being connected with an arm 123, said arm 123 also being connected with the lower end of a vertical 40 rocker shaft 124; the upper end of said rocker shaft 124 has a finger 125 projecting laterally therefrom which when the cam plate 371 is located in its downward position extends into the dotted line position 45 shown in Fig. 1, that is in the path of the downwardly extending flap 14 of the carton on the block b.

When the parts are in position with cam plate locked, and the finger 125 extending 50 into the path of the flap 15, then when the spider which carries the forming blocks rotates after the carton on the block a has had its bottom sealed and begins to move off and the block b begins to move through its 55 circular path of travel to bring it next into position previously occupied by the block a, the flap 15 will by its engagement with the finger 125 rock the shaft 124 and this in turn will swing the arm 123 in a horizontal 60 plane, thereby moving the connecting rod 122 and swinging the arm 121 in a horizontal plane, thus rocking the vertical shaft 117 sufficient to turn the finger 120 out of a locked position with relation to the lug 65 115 on the cam plate 371. This allows the

said cam plate to be lifted by the roll 34 under the stress of the spring 36 until the cam plate strikes the stop 375 and the glue roll will be carried outward by the slide 27 into operative position with relation to the flap 13.

The means for turning the rocker shaft 117 back again, to bring the finger 120 into a locking position after the spider 4 has rotated far enough for the second roll 59 to have performed its operation, is as follows: Secured to the vertical rocker shaft 124 is an arm 126 which is connected with one end of a rod 127 whose other end is connected with one end of an arm 128 pivoted on a 80 stud connected with the frame. Said arm carries at 129 a roller 130 which engages with the cam 131 mounted on shaft 92. Said cam 131 has an operative surface so that at the proper time in the rotation of 85 the shaft 92, (which is properly timed and controlled in its rotation by the driving shaft which drives the other mechanisms) the shaft 117 will rock in a direction the reverse of that in which it was actuated by the 90 engagement of the finger 125 by the depending flap of the carton on the block b, thus turning the locking finger 120 back into position over the lug 115 on the pivoted cam plate 371 and it remains in its locking position until it shall be again released by a depending flap on another carton. 95

The spider shaft 1 is driven by a main shaft 140 through any suitable connection. The connection shown is a sprocket chain 100 141 which runs over a sprocket wheel 142 on the main shaft and a sprocket wheel 144 on the spider shaft.

The shaft 92 is driven by gear connection 145 on the main shaft with the gear 146 on 105 the shaft 92.

The glue rolls 25 and 59 are supplied with glue by coming in contact at each rotation of the spider with a gluing roll 150, which is mounted on a shaft 151 on 110 which is mounted a wheel 152 driven by any suitable means. Said glue roll 150 dips into a glue tank 153. The shaft 151 carries a spur gear 154 which in turn meshes with a gear 155 mounted on a shaft 156, which carries a roll 157. Said roll 157 is smaller than the roll 150 and the bearings for the shaft 156 are so positioned that the roll 157 will very nearly come in contact with the roll 150. The two gears 154 and 155 bear 115 the same ratio to each other as the glue rolls 150 and 157, so that they will rotate at the same speed. The purpose of the small roll 157 is to regulate the thickness of the film of glue which will be carried by the 120 gluing roll 150. The bearings 158 for the shaft 156 may be adjusted to bring the roll 157 nearer to or farther away from the gluing roll 150 by means of the adjusting 125 screws 159. 130

Scrapers 160 are provided at the opposite sides of the gluing roll 157, to take off any glue that may be forced out sidewise from between the gluing rolls 150 and 157.

5 What I claim is:—

1. In a machine for folding and sealing the end forming flaps of a carton, the combination of a stationary former on which a carton is held with the end forming flaps extending beyond the end of the former, a rotary member, an oscillatable folding member carried by said rotary member, and means for causing said folding member to rock in the opposite direction to the direction of movement of the rotary member on which it is mounted and fold one of the carton flaps against the end of the former into a plane tangent to the arc of movement of the said folding member.
- 10 2. In a machine for folding and sealing the end forming flaps of a carton, the combination of a stationary former on which a carton is held with the end forming flaps extending beyond the end of the former, a rotary member, an oscillatable folding member carried by said rotary member, means for causing said folding member to rock in the opposite direction to the direction of movement of the rotary member on which it is mounted and fold one of the carton flaps against the end of the former into a plane tangent to the arc of movement of the said folding member, and a second folding member carried by the said rotary member, and stationary with relation thereto, so positioned that in the continued rotation of the said rotary member said folding member will engage the extending flap opposite the first folded flap and fold it against the end of the former into the same plane with the said first folded flap.
- 15 3. In a machine for folding and sealing end forming flaps of cartons, a former on which the carton is held in tubular form with distending flaps, a rotary member which rotates in one direction, an oscillatable folding member carried by said rotary member, means for causing said folding member to rock in the opposite direction to the direction of movement of the rotary member on which it is mounted, and fold one of the carton flaps against the end of the former, a second folding member carried by said rotary member so positioned that it will engage one of the distending flaps opposite the first folded flap after the first flap has been folded, and fold it up against the end of the former, and a glue roll carried by said rotary member so positioned that it will engage the said second folded flap after it has been folded.
- 20 4. In a machine for folding and sealing the end forming flaps of cartons while the carton is held in tubular form on a forming block, a rotary spider which rotates in a plane at right angles to the plane of the end of the block which holds the carton, a folder member mounted on said spider and means for causing said folder member to rock in a backward direction counter to the direction of movement of the spider, and fold one of the flaps of the carton, the said folder member moving in a path tangent to the end of the forming block against which the end flap is folded.
- 25 5. In a machine for folding and sealing the end forming flaps of cartons while the carton is held in tubular form on a forming block, a rotary spider which rotates in a plane at right angles to the plane of the end of the block which holds the carton, a folder member mounted on said spider, means for causing said folder member to rock in a backward direction counter to the direction of movement of the spider, and tangent to the end of the forming block to fold the first flap of the carton, means for causing said folder member to then rock forward in the general direction of movement of the spider and a second folder member carried by said spider which after the first folder member has performed its function engages a second flap opposite said first folded flap and folds it up against the end of the former, the said second folder member traveling in a path substantially tangent to the end of the forming block against which the flaps are folded.
- 30 6. A machine for folding and sealing the end forming flaps of cartons while the carton is held in tubular form on a forming block, having in combination a rotary spider which rotates in a plane at right angles to the plane of the end of the block which holds the carton, a folder member mounted on said spider, means for causing said folder member to rock in a backward direction counter to the direction of movement of the spider, and fold the first flap of the carton, means for causing said folder member to then rock forward in the general direction of movement of the spider, a second folder member carried by said spider which after the first folder member has performed its function engages a second flap opposite said first folded flap and folds it up against the end of the former, and a glue roll mounted on said spider which follows said second folder member and rides over the outer face of said second folded flap.
- 35 7. A machine for folding and sealing end forming flaps of cartons having in combination a rotary spider which rotates in a plane at right angles to the plane of the end forming flap of the carton and a glue roll having a spring-seated mount carried by the said spider.
- 40 8. A machine for folding and sealing end forming flaps of cartons having in combination a rotary spider which rotates in a plane at right angles to the plane of the end forming flap of the carton and a glue roll having a spring-seated mount carried by the said spider.

plane at right angles to the plane of the end of the block which holds the carton, a folder member mounted on said spider and means for causing said folder member to rock in a backward direction counter to the direction 70 of movement of the spider, and fold one of the flaps of the carton, the said folder member moving in a path tangent to the end of the forming block against which the end flap is folded.

5. In a machine for folding and sealing the end forming flaps of cartons while the carton is held in tubular form on a forming block, a rotary spider which rotates in a plane at right angles to the plane of the end of the block which holds the carton, a folder member mounted on said spider, means for causing said folder member to rock in a backward direction counter to the direction of movement of the spider, and tangent to the end of the forming block to fold the first flap of the carton, means for causing said folder member to then rock forward in the general direction of movement of the spider and a second folder member carried by said spider which after the first folder member has performed its function engages a second flap opposite said first folded flap and folds it up against the end of the former, the said second folder member traveling in a path substantially tangent to the end of the forming block against which the flaps are folded.

6. A machine for folding and sealing the end forming flaps of cartons while the carton is held in tubular form on a forming block, having in combination a rotary spider which rotates in a plane at right angles to the plane of the end of the block which holds the carton, a folder member mounted on said spider, means for causing said folder member to rock in a backward direction counter to the direction of movement of the spider, and fold the first flap of the carton, means for causing said folder member to then rock forward in the general direction of movement of the spider, a second folder member carried by said spider which after the first folder member has performed its function engages a second flap 110 opposite said first folded flap and folds it up against the end of the former, and a glue roll mounted on said spider which follows said second folder member and rides over the outer face of said second folded flap.

7. A machine for folding and sealing end forming flaps of cartons having in combination a rotary spider which rotates in a plane at right angles to the plane of the end forming flap of the carton and a glue roll having a spring-seated mount carried by the said spider.

8. A machine for folding and sealing end forming flaps of cartons having in combi- 130

nation a rotary spider which rotates in a plane at right angles to the plane of the end forming flap of the carton and a glue roll having a spring-seated mount carried 5 by the said spider, said spring-seated mount being movable radially with relation to the axis of rotation of the spider.

9. A machine for folding and sealing the end forming flaps of cartons having in combination a rotary spider, means carried thereby for successively folding two opposite flaps of the carton, a glue roll carried thereby which engages the said folded flaps, means for folding a third flap over said 15 previously folded and glued flaps, and a second glue roll which is carried by the spider into position to engage the third folded flap.

10. A machine for folding and sealing the end forming flaps for cartons having in combination a rotary spider, means carried thereby for successively folding two opposite flaps of the carton, a glue roll carried thereby which engages the said folded flaps, 20 means for folding a third flap over said previously folded and glued flaps, a second glue roll which is carried by the spider into position to engage the third folded flap, and a flap retainer which is carried by said 25 spider and engages the second folded flap after the first gluing roll has passed over the flap and before the third flap folder folds the third flap.

11. A machine for folding and sealing the end forming flaps for cartons, having in combination a rotary spider, means carried thereby for successively folding two opposite flaps of the cartons, a glue roll carried thereby which engages the said folded flaps, 30 means for folding a third flap over said previously folded and glued flaps, a second glue roll which is carried by the spider into position to engage the third folded flap, a flap retainer which is carried by 35 said spider and engages the second folded flap after the first gluing roll has passed over the flap and before the third flap folder folds the third flap, and a second flap retainer carried by said spider which engages 40 the third flap after it has been folded and before the second glue roll comes into engagement with said third flap.

12. A machine for folding and sealing the end forming flaps of cartons having in combination a rotary spider, means carried thereby for successively folding two opposite flaps of the carton, a glue roll carried thereby which engages the said folded flaps, means for folding a third flap over 55 said previously folded and glued flaps, a second glue roll which is carried by the spider into position to engage the third folded flap, a flap retainer which is carried by said spider and engages the second 60 folded flap after the first gluing roll has 65

passed over the flap and before the third flap holder folds the third flap, a second flap retainer carried by said spider which engages the third flap after it has been folded and before the second glue roll comes 70 into engagement with said third flap, a third flap retainer carried by the spider which engages the said third flap after it is glued, and a folding member which engages the fourth flap and folds it up against 75 the said third flap after it is glued.

13. A machine for folding and sealing the end forming flaps of cartons having in combination a rotary spider which rotates in a plane at right angles to the plane of 80 the folded end flaps, two folding members carried by said spider which successively engage two opposite distended flaps and fold them to partially form the end of the carton, a gluing device carried by said 85 spider into position to glue the second folded flap, means for folding the third flap and a second gluing mechanism carried by said spider in position to glue the third folded flap, said second gluing mechanism 90 being independent of said first gluing mechanism.

14. A machine for folding and sealing the end forming flaps of cartons having in combination a rotary spider carrying two flap 95 folding members and two gluing members, and means for rotating said spider to successively bring said folding members and gluing members into operative position to fold and to glue different flaps of the carton. 100

15. A machine for folding and sealing the end forming flaps of cartons having in combination a rotary spider carrying two flap folding members and two gluing members, means for rotating said spider to successively bring said folding members and gluing members into operative position to fold and to glue different flaps of the carton, means for folding a third and fourth flap of the carton and means for controlling 105 the movements of said several folding and gluing members in such manner that two opposite flaps will be first successively folded and then glued, then the third flap will be folded and glued, then the fourth 110 flap will be folded.

16. A machine for folding and sealing the end forming flaps of cartons having in combination a rotary spider which rotates in a plane at right angles to the plane of 115 the folded flaps, means carried by said spider for folding certain of the flaps, means carried by the spider for gluing certain of the flaps, and a flap retainer blade carried by the spider to support one of the 120 folded flaps until the next flap is ready to be folded, said retainer blade having an outer periphery which is curved on an arc of a circle concentric with the axis of rotation of the spider. 125

17. A machine for folding and sealing the end forming flaps of cartons, having in combination a rotary spider which rotates in a plane at right angles to the plane of 5 the folded flaps, means carried by said spider for successively folding certain of the flaps one over another, and a flap retainer blade carried by the spider to engage and support one of the folded flaps 10 until the next flap is ready to be folded over to retain said first flap in position.
18. A machine for folding and sealing the end forming flaps of cartons, having in combination a rotary spider which rotates 15 in a plane at right angles to the plane of the folded flaps, means carried by said spider for successively folding certain of the flaps one over another, and a flap retainer blade carried by the spider to engage and support one of the folded flaps 20 until the next flap is ready to be folded over said first flap, said retainer blade having an outer periphery which is curved on an arc of a circle concentric with the axis 25 of rotation of the spider.
19. A machine for folding and sealing the end forming flaps of cartons having in combination a block to receive a tubular carton, said block having an end against which the 30 flaps are folded, a rotary spider and a glue roll mounted on said spider in position to engage one of the folded flaps during the movement of the spider.
20. A machine for folding and sealing 35 the end forming flaps of cartons, having in combination a holder to receive a carton having distended flaps, a rotary member, means carried by said rotary member which during its rotation engages and folds certain of the flaps, and a glue roll mounted on said rotary member in position to follow after the folding and engage one of the folded flaps during the movement of said rotary member.
- 45 21. A machine for folding and sealing the end forming flaps of cartons, having in combination a block to receive a tubular carton with distended flaps, said block having an end against which the flaps are to be folded, a rotary spider mounted independent of said block, and a flap folder carried by said spider, which when the spider rotates moves adjacent the said block and engages with and folds one of the end forming flaps during the rotation of the spider.
- 50 22. A machine for folding and sealing the end forming flaps of cartons, having in combination a block to receive a tubular carton, said block having an end against which the flaps are to be folded, a rotary spider, a plurality of flap folders carried by the spider, means for actuating said flap folders to successively fold the flaps, and a flap retainer carried by said spider 55 which during the rotation of the spider
- engages the prior one of the said folded flaps to hold it in folded position until the next flap is folded up against the said previously folded flap.
23. A machine for folding and sealing 70 the end forming flaps of cartons having in combination a block on which the tubular cartons are mounted and having an end against which the flaps are to be folded, means for folding two opposite flaps against 75 the end of said block, a movable gluing device, means for moving said gluing device over the outer face of said two flaps, and means for causing the gluing device to skip an intermediate portion.
24. A machine of the character described 80 having a rotary spider, a slide mounted in said spider movable radially with relation to the axis of rotation of said spider, a gluing device carried by said slide, an arm pivotally connected at one end to the spider and pivotally connected at its other end to said slide, a projection on said arm and cam pivotally connected at one end to a fixed part of the machine, the other end of the cam 90 resting on the said projection from the arm of the slide, a spring which tends to thrust said slide radially outward and a stop which is adapted to engage said cam, and thereby through the engagement of said cam with 95 the projection on the slide-carried arm to limit the outward thrust of the said slide.
25. A machine of the character described 100 having a rotary spider, a slide mounted in said spider movable radially with relation to the axis of rotation of said spider, a gluing device carried by said slide, an arm pivotally connected at one end to the spider and pivotally connected at its other end to said slide, a projection on said arm, a cam pivotally connected at one end to a fixed part of the machine, the other end of the cam resting on the said projection from the arm of the slide, a spring which tends to thrust said 105 slide radially outward and a stop which is 110 adapted to engage said cam, and thereby through the engagement of said cam with the projection on the slide-carried arm to limit the outward thrust of the said slide, said cam being formed with a convex portion which during the rotation of the spider is adapted to engage said projecting portion on the slide-carried arm to compensate for the normally curved path of movement of the gluing device, and cause the gluing device to move for a limited distance in a 115 straight path.
26. A machine of the character described 120 having a rotary spider, a slide mounted in said spider movable radially with relation to the axis of rotation of said spider, a gluing member carried by said slide, an arm pivotally connected at one end to the spider and pivotally connected at its other end to said slide, a projection on said arm, a cam 125 130

- pivottally connected at one end to a fixed part of the machine, the other end of the cam resting on the said projection from the arm of the slide, a spring which tends to 5 thrust said slide radially outward, a stop which is adapted to engage said cam, and thereby through the engagement of said cam with the projection on the slide-carried arm to limit the outward thrust of the said slide,
- 10 said cam being formed with a convex portion which during the rotation of the spider is adapted to engage said projecting portion on the slide-carried arm to compensate for the normally curved path of movement
- 15 of the gluing device, and cause the gluing device to move for a limited distance in a straight path, a locking member which normally engages the said cam to hold it in a somewhat retracted position, a movable cart-
- 20 ton carrying member, means controlled by a carton carried by said carton carrying member to release said lock, and means which when said lock is released causes the cam to move to a position farther away from the
- 25 axis of rotation of the spider, whereby the straight line movement of the gluing member takes place in a line farther removed from the axis of rotation of the spider than when said cam is in its locked position.
- 30 27. A machine of the character described having a rotary spider, a spring-seated slide mounted in said spider movable radially with relation to the axis of rotation of said spider, a gluing member carried by said slide, a cam pivotally connected at one end 35 to the fixed part of the machine, a projection on said slide which during the rotation of the spider engages said cam, said cam being formed with a curved face of such form that when said projection rides on said curved face the said slide is caused to move radially inward and thereby compensate for the normally curved path of travel of the gluing member carried by the slide, and a member carried by said spider which also 40 engages with said cam during an intermediate portion of the engagement of said projection on the slide with said cam, whereby the said gluing device is caused to move in a retracted path for a predetermined distance.
28. In a machine for folding and sealing the end forming flaps of a carton, the combination of a statiorary forming block upon which the carton is held, a rotary carrier, 55 flap folders and flap gluing rolls mounted on said carrier, the said rotary carrier during its rotation on its axis causing the flap folders to fold two end flaps of the carton against the block and causing the gluing 60 rolls to pass over the folded flaps and apply a layer of glue thereto, both the flap folders and the gluing rolls passing over and continuing beyond the end face of the block after their separate functions are performed. 65
- In testimony whereof I affix my signature.

GEORGE A. ROBINSON.
